UNITED STATES PATENT OFFICE.

THOMAS H. DODGE, OF WORCESTER, MASSACHUSETTS, ASSIGNOR TO THE
WASHBURN & MOEN MANUFACTURING COMPANY, OF SAME PLACE, AND
ISAAC L. ELLWOOD, OF DE KALB, ILLINOIS.

BARBED FENCE-WIRE.

SPECIFICATION forming part of Letters Patent No. 250,899, dated December 13, 1881.

Application filed March 28, 1876.

To all whom it may concern:

Be it known that I, THOMAS H. DODGE, of the city and county of Worcester, and Commonwealth of Massachusetts, have invented 5 certain new and useful Improvements in Barbed Fence-Wire or Fencing; and I do hereby declare that the following is a full, clear, and exact description of the same, reference being had to the accompanying drawings, forming 10 a part of this specification, and in which—

Figure 1 represents a top or plan view of a section of my improved barbed fence-wire or fencing, as will be hereinafter more fully described. Fig. 2 represents a vertical central section on line A' B', Fig. 1. Fig. 3 represents a top or plan view of a section of my improved barbed fence-wire or fencing. Fig. 4 represents a section on line C' D', Fig. 3. Fig. 5 represents a cross-section on line M' N', Fig. 3; and Figs. 20 6, 7, and 8 represent sections on lines G', H', I', J', and K' L', Fig. 1; and Fig. 9 represents a section on line E' F', Fig. 3, looking in the direction of the arrow.

To enable those skilled in the art to which 25 my invention belongs to make and use the same, I will proceed to describe it more in detail.

In the drawings, the part marked A represents the main wire, which is to be run from 30 post to post in the usual manner. In applying the barbs B to the wire A, the latter is bent to form loops C, over which is forced or placed a barbed ring or link-piece, *a*, after which the barb part B is passed under the loop C and 35 above the link or ring-piece *a*, as indicated in Figs. 1, 2, 3, 4, and 5, when, by a slight blow or pressure applied to the part *b* of the loop C, the parts will be locked securely in position, and any strain thereafter upon the main wire 40 A will only tend to cause the parts to hug each other more closely.

The barbs are made or cut from sheet metal, 45 illustrations of which are shown in Figs. 1 to 9, inclusive, and which figures represent different forms or shapes of barbs. It will be noticed that in these forms the ring *a* is formed with projecting barbs, consequently four barbed ends are produced.

By constructing the barbed fence-wire or 50 fencing with the barbed part made from sheet metal the barbed part may be made wider than

the loop C, so that when the latter is drawn or forced down it will crimp or compress the former where it passes through the loop. The same result could be produced by having the 55 barbed part curved so that it would pass through the loop C readily, after which its ends could be pressed out flat, thereby forming shoulders on each side of the loop C; or the loops C may be formed so as to project through the ring at 60 a greater distance than is required to hold the barbed part, in which case the latter could be made wider than the loop and inserted in a diagonal position, so that when the loop and barbed part were forced down in their proper 65 relative positions, as respects the barbed locking-ring *a*, the sides of the loop would compress and crimp in the edges of the barbed part, as indicated in dotted lines, Fig. 4.

By my invention barbed fence-wire or fencing 70 can be made with comparatively very small wire, and yet have the barbs locked and secured firmly thereon, which cannot well be done so effectively by the old modes in use prior to my said invention. By my invention, if a barb happens to get broken or displaced, the fence can 75 be repaired very conveniently and quickly, and that, too, without detaching the main wire from the fence-posts. The barbs, too, may be cut from waste pieces of sheet metal, thereby economizing in the first cost of the construction of 80 the fence, as well as in the subsequent repair thereof.

Having described my improvements in 85 barbed fence-wire or fencing, what I claim therein as new and of my invention, and desire to secure by Letters Patent, is—

1. The barbed ring or link *a*, stamped or cut from sheet metal, in combination with the locking-barb B and a fence-wire, substantially as 90 and for the purposes shown and described.

2. As an improved article of manufacture, 95 barbed fence-wire in which a series of barbed links or rings, stamped or cut from sheet metal, and having holes in the center thereof, are secured at intervals to the main wire by barbed locking or fastening devices which hold the barbed rings flatwise against the fence-wire.

THOS. H. DODGE.
